Primary Examiner — T Chase Nelson*Assistant Examiner* — Jeff Lenard D Torres(74) *Attorney, Agent, or Firm* — Eversheds Sutherland (US) LLP(57) **CLAIM**

The ornamental design for a shoe sole, as shown and described.

DESCRIPTION

FIG. 1 is a bottom perspective view of a shoe sole showing the new design.

FIG. 2 is a front view of the shoe sole showing the new design.

FIG. 3 is a rear view of the shoe sole showing the new design.

FIG. 4 is a medial side view of the shoe sole showing the new design.

FIG. 5 is a lateral side view of the shoe sole showing the new design.

FIG. 6 is a top view of the shoe sole showing the new design; and,

FIG. 7 is a bottom view of the shoe sole showing the new design.

The broken lines show environmental structure that forms no part of the claimed design.

1 Claim, 7 Drawing Sheets(56)
